(No Model.).

M. J. LORRAINE.
CAR COUPLING.

No. 411,289.

Patented Sept. 17, 1889.

Fig. 1

UNITED STATES PATENT OFFICE.

MADISON J. LORRAINE, OF ST. LOUIS, MISSOURI, ASSIGNOR, BY MESNE ASSIGNMENTS, TO THE KEYSTONE CAR COUPLER COMPANY, OF ILLINOIS.

CAR-COUPLING.

SPECIFICATION forming part of Letters Patent No. 411,289, dated September 17, 1889.

Application filed May 7, 1888. Serial No. 273,132. (No model.)

To all whom it may concern:

Be it known that I, MADISON J. LORRAINE, of St. Louis, Missouri, have made a new and useful Improvement in Car-Couplings, of 5 which the following is a full, clear, and exact description.

This invention relates to that class of swing-head vertical plane couplers which rotate on trunnions or journal-bearings formed between 10 the ears of the draw-heads.

The improvement consists more especially in the improved means for preventing the hook or coupling-head, under draft, from being pulled out, whether the same be in either 15 a closed or open position.

An additional feature is the contour lines on which I construct what is known to the trade as the "Lorraine coupler."

In the annexed drawings, forming part of 20 this specification, Figure 1 is a diagram of the contour lines of one member of the coupling; Fig. 2, a horizontal section of both members of the coupling, the left-hand member having the coupling-head closed and the 25 right-hand one the coupling-head open. Fig. 3 is a vertical section on the line $x'y$ of Fig. 2.

The same letters of reference denote the same parts.

a is the draw-head; c , the coupling-head; 30 c' , Fig. 4, a projection or hook on the inner end of the tail of the coupling-head, which is designed to hook behind the locking-block l , and which is already described in my Letters Patent No. 341,027, May 4, 1886.

35 d d' are boss-shaped bearings on the inner faces of the respective ears of the draw-head.

d' d' are collars upon the coupling-head, which, when the coupling-head is in position, partially surround the said bearing d d' .

40 l is a shouldered key; l' , the lower part or stem of the key, made smaller than the upper part.

l is the opening in the coupling-head, into 45 which the key fits when dropped to lock the coupling-head.

l' is a curved slot in the coupling-head connected with the opening l , the curve of the slot being struck from the center of the bearing d , in which the key-stem l is held when 50 the coupling-head is open, and in that position it serves to keep the coupling-head

from falling or being pulled out of the draw-head.

The action of this improved coupling is analogous to that of other couplings of the 55 class under consideration. When the coupling-head is locked, as in the left-hand member of Fig. 2, the key falls through the opening l' , and by means of the shoulder l'' of the coupling-head the coupling-head is locked 60 against any rotary or longitudinal movement. When the key l is raised, as in Fig. 3, the coupling-head becomes unlocked, and it can be turned on the bearings d , and as it turns the key-stem l' enters into the slot l , and the 65 bottom of the key proper l rides on the top of the rearward arm of c , as shown in Fig. 3. The rear end of the collar $d' d'$ being cut away, the coupling-head c could easily be withdrawn were it not for some other retaining agency; but, owing to the combination of 70 the key with the inner or rearward arm of the coupling-head, as described, it is impossible to pull out the head, whether it is in a closed or an open position.

I do not confine myself to the exact shape of the key or opening shown, as any desired shouldered key that will fulfill the purpose intended can be used; nor do I confine myself to the exact shape of the rearward end 80 of the coupling-head, or the exact location of the key, or the slot l' , or other relative parts.

In my Letters Patent No. 353,330 I show certain contour lines which differ from the lines shown in the patent of Eli H. Janney, No. 85 212,703, dated February 25, 1879, and particularly in that the inner line, marked X X, Fig. 11, of said patent, and shown rounded therein, is in the present case straight. Said rounded line in Janney's is caused by its being part of a "continuous outline formed by two equal semicircles in reversed position." Having in practice found that this rounded surface (line) wearing against the opposing rounded surface (which it does by reason of 90 a constant lateral play of the coupled parts) soon becomes flat, and having also further found by practical tests that a draw-head having said inner face parallel with the front face of the draw-head tends to slip laterally 100 out of engagement with the opposing draw-head, I design the present contour so that the

inner face inclines slightly toward the front face thereof without at the same time essentially abandoning the flat surfaces described. This particular construction I find is a desirable one in that it gives the opposing hooks a better grip upon each other in pulling. I have further learned in constructing my coupler as heretofore, with the flat faces shown, respectively, at D E and H I, Fig. 1, that when the opposing members came gently together they did not readily couple, but that a somewhat smart shock was necessary to effect the coupling, and I now, therefore, make these surfaces slightly curved, and they more readily slip on each other. Other necessary changes are made in the lines, so that my coupler will interchange properly with what is now known as the "M. C. B. standard." The radii, extent, and relative location of the curves and the extent and location of the tangent composing the contour in question are shown in Fig. 1 of the drawings.

So far as the contour is concerned, the improvement relates to all swing-head vertical-plane couplers—that is, to those in which the coupling-head is pivoted on a pin, as well as to those in which the coupling-head is journaled upon bearings, as shown. Nor do I desire to be restricted to any special form of locking-key, so long as one is used that is adapted to the other conditions, as described and claimed. c^{10} is called the "nose" of the coupling-head, and c^{20} is the recess into which the nose of the opposing coupling-head fits when the two members of the coupling are engaged.

I claim—

1. A car-coupling member of the type described, the contour of whose outer end consists of the compound curves I H G and D E F, united by the tangent G F, substantially as and for the purposes described. 40

2. A car-coupling member of the type described, the nose c^{10} of which and the recess c^{20} , into which the nose of the opposing car-coupling member fits when coupled, are formed with the curves G H and E F, united by the tangent G F, slightly inclined toward the outer face H I, substantially as shown 45 and described. 50

3. The combination, in a car-coupling, of a draw-head having bearings $d d$, the coupling-head having integrally-cast collars $d' d'$ and curved slot l^3 , and a shouldered locking-pin 55 with a reduced stem engaging said slot and resting on inner arm of the coupling-head when open and dropping to lock it when closed.

4. The combination, in a car-coupling, of a draw-head, a pivoted coupling-head having a curved slot l^3 , and a shouldered locking-pin with a reduced stem engaging with said slot and resting on the inner arm of the coupling-head when open and dropping to lock it when 60 65 closed, substantially as set forth.

Witness my hand this 4th day of May, 1888.

MADISON J. LORRAINE.
